DESIGN FOR AN EXTENSION SERVING TABLE

Hollis S. Baker, Grand Rapids, Mich., assignor to Baker Furniture, Inc., Grand Rapids, Mich., a corporation of Michigan

Application August 20, 1945, Serial No. 121,561

Term of patent 7 years

(Cl. D33—14)

To all whom it may concern:

Be it known that I, Hollis S. Baker, a citizen of the United States, residing at Grand Rapids,
in the county of Kent and State of Michigan,
have invented a new, original, and ornamental Design for an Extension Serving Table, of which the following is a specification, reference being had to the accompanying drawing, forming a part thereof, in which:

The figure is a perspective view of an extension
serving table showing my new design.

I claim:

The ornamental design for an extension serving table, as shown.

HOLLIS S. BAKER.
